UNITED STATES PATENT OFFICE.

WALTER G. BROWN, OF LOS ANGELES, CALIFORNIA.

SUITCASE WARDROBE.

Application filed July 21, 1922. Serial No. 576,580.

To all whom it may concern:

Be it known that I, WALTER G. BROWN, a citizen of the United States, residing at Los Angeles, in the county of Los Angeles and State of California, have invented new and useful Improvements in Suitcase Wardrobes, of which the following is a specification.

My invention relates generally to wardrobes, and more particularly to a combined wardrobe and suitcase in which the wardrobe is capable of being folded in a compact position within a suitcase, or extended to provide a wardrobe in which the clothes and other contents of the suitcase can be held in suspended position.

Although I have herein shown and described only one form of combined wardrobe and suitcase embodying my invention, it is to be understood that various changes and modifications may be made herein without departing from the spirit of the invention and the spirit and scope of the appended claims.

In the accompanying drawings,

Figure 1 is a view showing in front elevation one form of combined wardrobe and suitcase embodying my invention, with the wardrobe frame in fully extended position and encompassed by a canopy.

Fig. 2 is a side elevation of the wardrobe and suitcase shown in Fig. 1.

Fig. 3 is a perspective view of the wardrobe frame in fully extended position and with the inclosing canopy partly broken away.

Fig. 4 is a top plan view of the suitcase shown in Fig. 3 with one side of the latter in open position.

Fig. 5 is a perspective view of the wardrobe frame partly in folded position, the suitcase being omitted to reveal parts not otherwise disclosed.

Fig. 6 is a fragmentary view partly in section of the clothes hanger supporting means comprised in the wardrobe shown in Fig. 5.

Figs. 7, 8 and 8^a are views showing in side elevation the parts comprised in the con-

nection for the brace rods of the wardrobe frame shown in the preceding views.

Fig. 9 is a detail showing the brace clamp.

Fig. 10 is an enlarged sectional view of the connection between the floor engaging brace and the wardrobe frame.

Fig. 11 is an enlarged detail view partly in section showing the link connection between the side portions of the wardrobe frame.

Fig. 12 is a view similar to Fig. 11 showing the hinge connection between the side portions and the main frame of the wardrobe.

Fig. 13 is a fragmentary perspective view partly in section showing the manner in which the canopy is supported upon the wardrobe frame.

Fig. 14 is a fragmentary sectional view showing the attaching means for the lower ends of the wardrobe frame with respect to the side portion of the suitcase.

Similar reference characters refer to similar parts in each of the several views.

Referring specifically to the drawings, my invention in its present embodiment comprises a suitcase which includes a body portion 15 on which are hingedly supported side portions 16 and 17. The side portion 16 is adapted to occupy the closed position as shown in Fig. 3 or the open position as shown in Fig. 4, and the hinge connection between this side portion and the body portion is supposed to be permanent. However, the hinge connection between the side portion 17 and the body portion is designed to permit of the ready detaching of the side portion from the body portion, and to this end hinges 18 are provided in which one section thereof is permanently secured to the body portion and the other section permanently secured to the side portion, and the connection between the two is such that by a longitudinal shifting of the side portion, the hinge sections can be disengaged to permit of the detaching of the side portion.

The side portion 17 is extensibly associated with the body portion of the suitcase through the medium of a wardrobe frame. The side portion 17 is extensibly associated with the body portion of the suitcase through the medium of a wardrobe frame.

As clearly shown in Fig. 5, this wardrobe frame includes a main frame 19 which is adapted to be fitted within the body portion 15 of the suitcase and secured therein by screws 20 extended through the suitcase and threaded in the corners of the frame. Extending from the corners of the frame 19 are rods 21 to which are hingedly connected the side members of the wardrobe frame. This hinge connection between the side members and the rods 21 is clearly shown in Fig. 12, and as here shown sleeves 22 are slidably mounted upon the rods 21 to occupy spanning or nonspanning position with relation to the hinge connection to prevent or allow of the breaking of the joints. These sleeves 22 are all rigidly connected to each other by means of rods 22^a.

In order to provide a compartment within a suitcase for the reception of wearing apparel and irrespective of the position of the wardrobe frame, a partition P is secured to the rods 22^a and the sleeves 22. The arrangement of the partition P is such that when the rods and sleeves are in folded position within the suitcase, the partition is disposed substantially midway between the sides 16 and 17 so as to provide a compartment in which shirts, hats and similar apparel can be stored, thereby still allowing the suitcase to be used in the regular manner. However, when the rods and sleeves are in extended position, the partition is naturally lowered, but it still serves as a support for the apparel and thus functions as a dresser or chiffonier.

Each side member includes two sections designated 23 and 24, and the lower section 24 is hingedly connected to the upper section 23 through the medium of a link 25 which, as clearly shown in Fig. 11, is pivotally connected by pins 26 to the rods comprising the members so that the lower section 24 is capable of being folded upon the upper section 23. Sleeves 27 are slidably mounted upon the rods of the upper section 23 so as to engage or disengage the link 25. When the sleeves 27 are in covering position with respect to the links 25 it will be clear that the section 24 is held in fully extended position with respect to the section 23 as clearly shown in Fig. 3. However, when the sleeves are moved to uncovering position with respect to the links, the section 24 can be readily folded upon the section 23 to occupy a compact position within the body portion of the suitcase.

The sections 23 and 24 each include transverse brace rods 28 and 29, the latter also serving the purpose of limiting the downward movement of the sleeves 22 and 27 so that the sleeves will occupy covering position with respect to the hinge connections.

In conjunction with the side members of

the wardrobe frame, extensible straps 30 and 31 are adapted to be employed, and these straps at their upper ends are threaded about the brace rods 28, while at their lower ends they are connected to bars 32 secured to the inner side of the side portion 17. These straps provide further means for maintaining the side members of the frame in extended position.

As clearly shown in Fig. 14, the lower ends of the rods constituting the sections 24 are recessed to accommodate studs 24^a which are hingedly secured to the head 24^b of a bolt 24^c threadedly fitted in the side portion 17 of the suitcase and provided with a cap 24^d.

By the foregoing arrangement, it will be clear that the rods of the sections 24 are detachably associated with the side portion 17 of the suitcase to permit of the folding of the sections and the vertical positioning of the sections upon the side portion when the former are in extended position. It will be clear that the straps 30 and 31 will serve to maintain the side members of the frame in upright position and their lower ends in proper relation with respect to the studs 24^c. However, in order to further brace the side portions of the frame, converging brace rods 34 are provided upon the upper sections 23. These brace rods, as clearly shown in Fig. 3, are arranged in pairs with each pair of rods rigidly connected by brace rods 34^a. The two pairs of brace rods 34 are detachably connected to each other so as to allow of the separation thereof when the sections 23 are folded.

As clearly shown in Figs. 7, 8 and 9, one pair of rods 34 is provided at their meeting ends with a plate 35 having a slot 36 provided with an enlarged end and a restricted portion as clearly shown in Fig. 8. The other pair of rods 34 is also provided with a plate 37, and this plate is slotted as indicated at 38. A bolt 39 is adapted to extend through the slots 36 and 38; the head of the bolt being passed through the enlarged end of the slot 36. After the bolt has been applied, a wing nut 40 is threaded on the bolt and when properly adjusted will effect a secure clamping of the plates 35 and 37 together. This obviously provides a rigid connection between the two pairs of rods so as to effectively maintain the sections 23 in proper spaced relation. By virtue of the formation of the slot 36, it will be clear that after the bolt has been once applied it is unnecessary to remove the same to effect the disconnection of one pair of rods from the other. A mere loosening of the nut 40 is all that is necessary, and this nut is retained against displacement from the bolt by means of a cotter pin 41.

As a further means for rigidly supporting the wardrobe frame against overturning, brace rods 42 are rotatably sustained on the

rods of the lower sections 24 by sleeves 43 which, as clearly shown in Fig. 10, carry set screws 44 adapted to engage the rods for locking the sleeves in any adjusted position. 5 When in active position, the rods 42 are inclined so that their lower ends engage the floor and reinforcing rods 47 connect the sleeves 43 with the rods 42 to effectively brace the latter. However, when the rods 10 42 are not in use, they may be swung inwardly upon the sections when the screws 44 are adjusted to disengage the rods of the sections.

For the purpose of supporting clothes in 15 hanging or suspended position within the wardrobe frame when the latter is in extended position, clothes hangers 48, such as that shown in Fig. 3, are employed in conjunction with rods 49 secured at their rear 20 ends to the rods 22^a. These rods 49 slidably receive split tubular rods 50, the latter being bent downwardly at their outer ends as indicated at 51 to provide handles for the 25 purpose of manipulating the rods as will be understood.

The forward ends of the rods 49 are supported by transverse rods 52, the latter being extended from the forward pair of sleeves 22 as clearly shown in Fig. 5. These 30 rods are preferably welded or otherwise secured to the rods 49 as clearly shown in Fig. 6. As shown in Fig. 5, the rear ends of the rods 50 are formed with lips 53 designed for the purpose of engaging the 35 clothes hangers, so that when the rods are pulled outwardly a similar movement is imparted to the clothes hangers.

The clothes hangers 48, in the present instance, each comprises a frame and laterally 40 extending arms 54 which are curved downwardly at their outer ends so that when in reposing position upon the rods 50, they will serve to sustain the frame in vertical 45 position and against accidental displacement from the rods. As clearly shown in Fig. 6, these downturned ends of the arms 54 are disposed in the path of movement of the lips 53 to effect the forward movement 50 of the hangers when the rods are pulled outwardly.

As clearly shown in Figs. 4 and 5, the rods 49 are arranged to support the clothes hangers adjacent one end of the suitcase so that a space is provided at the opposite end 55 of the suitcase and at one side of the wardrobe frame for the purpose of accommodating a clothes bag indicated at 55. It is to be understood that the clothes bag is sustained by means of its draw string within 60 the main frame of the wardrobe as indicated in Fig. 4.

As clearly shown in Fig. 1, the wardrobe frame is adapted to be encompassed by a curtain or canopy designated at K. This 65 canopy is suspended from certain of the

rods 22^a, and as clearly shown in Fig. 13, a multiplicity of relatively small rings 56 are loosely mounted on these rods, and the canopy is connected to the rings so as to permit of the ready adjusting of the curtain upon 70 the rods. Draw strings 57 and 58 are provided and associated with the canopy K so that by pulling the strings 57 the canopy may be opened at its forward side while upon pulling the strings 58 the canopy will 75 be closed.

Especial attention is called to the wardrobe frame mounted in the removable side portion of the suit case, the body of the portion of the suit case fitting the top of the 80 frame, and the straps connecting the side portion of the suit case to the top of the frame.

What is claimed is:

1. In combination, a suitcase having a removable side portion, and a wardrobe frame connecting the body portion of the suitcase with the removable side portion, said frame being collapsible so as to be folded within the suitcase, and extensible to provide a 90 wardrobe and to support the suitcase in elevated position and straps connecting the side portion of the suit case to the upper part of the frame.

2. A wardrobe frame comprising a main body member, side members formed of sections foldable upon each other, means for maintaining the sections in extended position, brace rods connected to certain of the sections and detachably connected to each other, and other brace rods slidably sustained on the lower sections of the side members to occupy folded or extended positions a suit case body fitting the top of the frame, a suit case side piece under the frame, and straps connecting the suit case side to the upper part of the frame.

3. A wardrobe frame comprising a main body member including rods, sleeves slidably mounted on the rods and rigidly connected to each other, side members including sections hingedly connected to each other and to said rods, sleeves on certain of the sections for engaging the hinge connections between the sections to maintain the sections 110 in extended position, the first mentioned sleeves being slidable to engage the hinge connections between the rods and the corresponding sections for maintaining the latter in extended position, and brace rods connecting certain of the sections and detachably associated with each other for maintaining said sections in proper spaced relation when in extended position.

4. A wardrobe frame comprising a main 125 body member including rods, sleeves slidably mounted on the rods and rigidly connected to each other, side members including sections hingedly connected to each other and to said rods, sleeves on certain of the 130

the sections for engaging the hinge connections between the sections to maintain the sections in extended position, the first mentioned sleeves being slidable to engage the hinge connection between the rods and the corresponding sections for maintaining the latter in extended position, and transverse brace rods on the sections for limiting the downward movement of the sleeves.

5. A suit case body, a removable side on 10 suit case body, a wardrobe frame fitting in the removable side and supporting the suit case body, and straps connecting the removable side to the upper part of the frame.

In testimony whereof I have signed my 15 name to this specification.

WALTER G. BROWN.
